UNITED STATES PATENT OFFICE.

ERNEST M. SKINNER, OF BOSTON, MASSACHUSETTS.

AUTOMATIC MUSICAL INSTRUMENT.

1,192,005.

Specification of Letters Patent. Patented July 25, 1916.

Application filed May 28, 1915. Serial No. 30,942.

To all whom it may concern:

Be it known that I, ERNEST M. SKINNER, a citizen of the United States, and a resident of Boston, in the county of Suffolk and 5 State of Massachusetts, have invented certain new and useful Improvements in Automatic Musical Instruments, of which the following is a specification.

This invention has relation to automatic 10 musical instruments and more particularly to those instruments which comprise a plurality of groups of sounding devices, such for example as a pipe organ.

One of the objects of the invention is to 15 secure the same musical effect as is produced by the several instruments of an orchestra. Ordinarily in an orchestra, each instrument produces a succession of single notes, and, to produce a chord, several instruments must 20 be caused to speak simultaneously. For instance, to produce a chord of the key of *c*, the lower *c* may be sounded by a French horn, the *c* above by a clarinet, the *g* by an oboe, and the *c* above by a flute. Thus there 25 is secured an independence of voices, which is not possible in an instrument operated by a single key board; for example, in a pipe organ, if the flute stop be drawn, all of the notes of the chord will sound a flute 30 tone, and the same is true of any other stop. Hence one of the results which I desire to achieve by my invention is the independence of voices in a pipe organ, or other instrument containing groups of sounding devices, 35 so that chords may be sounded in which each of the several notes is produced by the pipe or sounding device of only one of the different groups, and thus secure the effect of different instruments of an orchestra. Heretofore this has been practically impossible, 40 in an automatic instrument, because of the great width of the tracker board and the note sheet or selector. For example, to control the sounding devices of a chromatic 45 scale of three octaves, a tracker board heretofore had to have thirty-six air ducts or other equivalent means for controlling the sounding devices, and the music sheet or selector had to be correspondingly wide. 50 Hence, in a pipe organ having, for instance, only four stops, or four groups of pipes, to permit the formation of a chord comprising a single note from each group of pipes, the tracker board had necessarily to have one

hundred and forty four ducts. Therefore 55 in any organ or like collection of sounding devices such as would ordinarily be employed, the tracker board and the selector or music sheet had to be of such great width as to render their use practically prohibitive.

A second object of my invention is to provide such a combination and arrangement of devices controlled by the note sheet or selector, that a tracker board which is 65 relatively narrow may be used for a relatively large number of groups of sounding devices, and at the same time the independence of voices of the several groups to which I have made reference is secured. 70

I am able to secure the desired results by employing a tracker board having ducts or equivalent devices for operating note controllers no greater in number than the twelve tones of a chromatic scale of one octave, and additional controllers for selecting for operation any one of several octaves in which the desired tone is to be produced. In this way, for a group of sounding devices for producing the chromatic tones of three 75 octaves, the tracker board would have a group of twelve ducts controlling twelve note controllers, and in addition a second group of three ducts for selectively controlling the three second-mentioned controllers. 80 The thirty-six tones can thus be produced, in sequence if desired, in the three octaves by operating the three second-mentioned controllers one after the other, so as to select for operation the next higher octave on the 85 completion of each. Hence a narrow tracker board having only fifteen ducts or their equivalents will control a group of thirty-six pipes or other sounding device. For the twelve sounding devices for each additional 90 octave, there will be added to the ducts in the tracker board only one duct for controlling an additional controller.

I preferably employ a group of note controllers and additional controllers for each 100 complete group of sounding devices, and so arrange the connections that each of said groups of controllers can control each group of sounding devices, through the medium of suitable draw switches which may, if desired, be under manual control, in consequence of which an operator or player can 105 produce any desired tone color and render

any composition according to his own interpretation. This is all rendered possible because of the small space in a tracker board necessary to control an entire group of sounding devices.

A third object of the invention, however, is to provide for the automatic control of the several draw switches by the selector or note sheet, without materially increasing the width of the sheet and tracker board. To this end, I provide a novel arrangement of parts, in consequence of which, by the use of a selector-controlled controller supplemental to those heretofore mentioned, one of the groups of note controllers may be utilized for causing the operation of a large number of draw switches, or combinations of draw switches, so as to condition the various groups of sounding devices for operation. That is, a group of note controllers, which is used for causing the several sounding devices of a sub-group to speak, may also be utilized for causing the operation of the draw switches, by the operation of a selector-controlled controller. In this way, the width of the selector or music sheet is reduced to a minimum. For example, in an instrument possessing twelve groups of sounding devices, each having three octaves, I am able, with a tracker board having but sixteen ducts and a selector of corresponding narrow width, to select for operation any one or more of said groups of sounding devices, and to cause the production of sound from each of the thirty-six devices of each group so selected. And, even when the tracker board has several sections, each section having a series of primary ducts, and additional ducts, but one supplemental duct in the entire board is necessary in order to control all the stops.

On the drawings,—Figure 1 represents, conventionally and diagrammatically, a portion of a pipe organ embodying my invention in its simple form. Fig. 2 illustrates, conventionally and diagrammatically, a pipe organ embodying the invention and having four groups of sounding devices and draw switches therefor. Fig. 3 represents, conventionally and diagrammatically, a pipe organ embodying the invention, in which I am able to cause the independent operation of four groups of sounding devices. Figs. 4 and 5 illustrate portions of the draw-switch operating mechanisms. Figs. 6 and 7 illustrate more or less conventionally and diagrammatically the draw-switch operating mechanism, which may be employed in the instrument shown in Figs. 2 and 3. Fig. 8 illustrates a portion of a selector or music sheet.

It will be understood that the invention is not limited to the particular embodiment which I have illustrated and shall subsequently describe, nor to any particular

groups of sounding devices, nor to the particular mechanism by which they are caused to produce their respective tones, nor to any particular system of control, *i. e.*, pneumatic, electrical or mechanical, as persons skilled in the art on becoming acquainted with the generic or basic principles utilized in the invention, as explained herein, have at hand various equivalents which may be employed for the several instrumentalities, which I shall describe, without departing from the spirit and scope of the invention. It will further be understood that, for the purposes of illustration, the invention is shown conventionally and diagrammatically, and that I have omitted from the drawings as much mechanism as is possible, to prevent confusion or too great complication.

I will first explain a simple embodiment of the invention, and reference may therefore be had to Figs. 1 and 2. In these figures, which represent a portion of a pipe organ, 10 indicates a tracker board which, if the note controllers are pneumatically operated, is provided with twelve ducts, equal in number to the tones of a chromatic scale from *c* to *b*, as indicated by these characters on the drawings. Each duct 11 is connected to and controls a pneumatic note controller 12, to close a branch electric circuit by which some corresponding sounding device will be conditioned for operation or caused to speak or sound. These branch circuits are indicated in part at 13 and receive energy from a main circuit 59 which has the generator 59'. The entire group A³ of sounding devices comprises pipes turned to furnish the tones of a chromatic scale of three consecutive octaves, and is divided into sub-groups A B C, one for the sounding devices of each octave. Each of the corresponding pipes of the sub-groups, say those for producing *c*#, may be caused to speak by the registration of an aperture in the note sheet with the corresponding duct *c*# in the tracker board. To accomplish this, I employ three additional pneumatic controllers A' B' C' respectively to operate switch bars 14, 15, 16, of any suitable form, said controllers being operated by the opening of the ducts A² B² C² in the tracker board 10, as shown in Fig. 2. The switch bar 14 is shown conventionally as carrying a series of contacts 17 respectively connected by conductors 18 with the electromagnetic valve-controllers 211 of the pipes of the sub-group A; switch bar 15 is suitably equipped with contacts 19 connected by conductors 20 with the controllers for the pipes of sub-group B; and switch bar 16 has like contacts 21 connected by conductors 22 with the valve controllers for the pipes of sub-group C. All said contacts on each of the switch bars may be electrically connected with the respective branch circuits 13 upon movement of the

said bar to the left to close the branch circuits through the respective pipe controllers and thus condition the pipes to speak. As shown in the diagram in Fig. 2, the bar 15
 5 has been actuated by controller B', and hence, upon the actuation of any one of the note controllers 12, the corresponding pipe of sub-group B will speak to produce a tone in the middle octave. After operating said
 10 note controllers the controller C' (for instance) may be actuated, and controller B' released, and thereupon, on reoperating the note controllers, the sub-group C of the pipes may be caused to speak and produce the
 15 tones of the high octave. I preferably employ that type of additional controller, which, on being actuated, remains locked in position until another of the group is operated and is then released; and to this
 20 end I have conventionally illustrated a spring-tensioned locking bar 23 having holes through which pins 24 on the switch bars pass. These pins have tapering enlargements 25 which will lift the bar 23 when one
 25 of the switch bars is moved to the left, so as to release the previously locked switch bar, after which the bar 23 will drop to lock the switch bar thus moved to active or operative position. On being released, the switch
 30 bars may be moved to inactive position by springs 26. In lieu of this conventional mechanism, any other suitable means may be provided for locking and releasing the switch bars. I may, if desired, however,
 35 employ controllers that remain in active or operative position only so long as a perforation registers with the corresponding duct of the tracker board.

Preferably each entire group of pipes is
 40 controlled by what I may term a draw switch, which may be of any suitable type such as conventionally illustrated at 27, so that the pipes will remain mute unless the switch has been moved either manually or
 45 automatically to operative position. In the diagram, the draw switch 27 has contacts 31 which complete the branch circuits 13, 18, 13, 20, and 13, 22 through the pipe controllers 21 by the branch circuits 32.

50 From the foregoing description, it will be observed that the three sub-groups A, B and C of the entire group A³ of pipes or sounding devices are controlled by a series of note controllers which in number do not
 55 exceed the pipes of a single sub-group, and that, by the aid of the additional controllers A', B', C', any sub-group may be selected for operation, thereby reducing to a minimum the number of ducts for the controllers,
 60 the width of tracker board and the note sheet or selector which co-operates therewith.

Another important feature of the invention resides in the mechanism by which the draw switches may be automatically operated under the control of the selector or

note sheet by the addition of a supplemental controller and a duct or its equivalent in the tracker board. In Fig. 2, I have shown conventionally four draw switches, to wit: that at 27 previously referred to, and three
 70 additional draw switches 28, 29 and 30. I have also indicated four groups of sounding devices A³, D, E and F, (only one sounding device of each group being shown, for simplicity of illustration) each preferably consisting in practice of three sub-groups of pipes or their equivalents for producing the tones of a chromatic scale of three octaves, such as shown in Fig. 1. Corresponding branch circuits 33, 34 and 35 (similar to
 75 those at 32) include the contacts of the draw switches 30, 31 and 32, and the electromagnetic valve-controllers of the groups D, E and F of sounding devices. Hence the branch circuits 32, 33, 34 and 35 may be
 80 closed, or conditioned for the transmission of the electric current, by moving their respective switches to the left, and, after this has been done, the various sounding devices will speak according to the operation of the
 85 primary and additional controllers on the registration of the perforations in the selector or music sheet with the ducts in the tracker board.

For operating the draw switches automatically, I provide a switch bar 36, shown as located in proximity to those at 14, 15, 16 and operated by a pneumatic 37 connected by a duct 371 with a duct 372 in the tracker board. Said switch bar is shown conventionally as carrying contacts 38, equal in number to the groups of sounding devices, and these contacts 38 may be moved into electrical connection with contacts in the circuits 13, to close branch circuits 39
 100 through electromagnetic controllers 40 which cause or control the operation of the draw switches by any suitable mechanism. In Fig. 2 only four groups of sounding devices are illustrated, but a sufficient number
 105 of contacts 38 is shown to control twelve of such groups. The branch circuits 39 are connected with the main circuit 59 by the return conductor 139. On the energization of any one of the controllers 40, a valve will be
 110 opened to permit the passage of air from the trunk 41 to operate a corresponding pneumatic 42, which, through intervening mechanism to be explained, actuates one or more of the draw switches. Each of the draw
 115 switches is provided with a plurality of jacks 43, each pivoted midway between its ends, and these are arranged in rows, which equal in number the tertiary controllers 40. These jacks may be tilted or set, by mechanism
 120 subsequently to be described, so as to be in position to be engaged by actuating mechanism operated by the pneumatics 42. This actuating mechanism may be of the usual character and as shown consists of a series of
 125

pairs of bars or fans 44, 45, which extend beneath the draw switches in proximity to the jacks, as shown in Figs. 4 and 5. The fans are carried by bell crank levers 46, 47, the shorter approximately horizontal arms of which extend toward each other, and are engaged by adjustable nuts 48 on rods 49. Each rod 49 is shown as pivoted to a lever 50, which in turn is connected by a rod or link 51 to the movable portion of one of the pneumatics 42. According to the position of the jacks on the series of draw switches, upon the operation of one of the pneumatics, the switches will be moved into or out of active or operative position, by the engagement of the fans 44 or 45 with the jacks. Each jack may be tilted or set so that one end or the other will extend into the path of movement of one of the fans 44, 45, as will be clearly understood from an inspection of Fig. 4. As there shown, the draw switch 27 is supposed to be in inactive position, and the middle jack is tilted so that its right end extends into the path of movement of the fan 44 of the middle pair of bars. Now, upon the actuation of the corresponding pneumatic 42, the fans 44, 45, will be swung toward each other and the draw switch will be moved to the left or to active position, so as to condition for operation the group A² of sounding devices. The several jacks on the draw switches are set in position at the will of the operator according to any predetermined plan, and, after having once been set, the draw switches will be moved out and in automatically under the control of the note sheet or selector. To accomplish the automatic operation of the draw switches, I may employ a plurality of pneumatics 52, operatively connected to a wind trunk 56 and arranged over the draw switches and extending across them, as shown in Figs. 4 and 7. Each pneumatic extends across the draw switches and is arranged to tilt or set all of the jacks of one transverse row on the draw switches in one position or the other according to the positions, out or in, of said draw switches. In order to set a jack on any certain draw switch in position, so that, when the corresponding pneumatic 42 is operated the draw switch will be moved into active position, it is first necessary for the operator manually to draw out said switch, which brings the right end of the jack (see Fig. 4) under the corresponding pneumatic 52, and then to cause the operation of the said pneumatic so as to depress said right end of the jack into the path of movement of the corresponding fan 44. The other jacks in the same row will not be affected or else will be reset to lift their right ends into inactive position, since their supporting switches will have been left in inactive position by the operator. The operator then manually returns the previously drawn-out

draw switch to inactive position, and then proceeds to set the jacks on such other draw switches as may be desired. Many different combinations of the groups of sounding devices may be effected by initially positioning the jacks on the draw switches, and this can be done by drawing out several switches concurrently and setting the corresponding jacks thereon by the operation of one of the associated pneumatics 52.

The jack-setting pneumatics 52 may be controlled by any suitable means adapted to be actuated by the operator. I have conventionally illustrated in Fig. 7 a plurality of branch circuits 55, each branch circuit including an electromagnetically-operated valve 53 for one of the pneumatics 52, and a circuit closer or push button 54. The main circuit, with which the branch circuits are connected, is indicated at 57, and it may derive current from circuit 59 and the generator 59' by closing a switch 58, thereby opening the circuits 13. The push buttons 54 may be arranged below the key beard of the organ, or on one side thereof, and they may be numbered serially 1, 2, 3, 4, etc., according to the corresponding pneumatics, rows of jacks, pack-actuating bars, and the associated pneumatics 42 and branch circuits 39.

For simplicity of explanation, let it be assumed that the four groups of sounding devices A², D, E and F, indicated in Fig. 2, are pipes for producing the tones of the French horn, the flute, the clarinet and the oboe, respectively. The perforated note sheet or selector for example, contains printed directions stating that, during the rendition of the musical composition, the following combinations or arrangements of groups will be used in sequence:—first, clarinet and oboe; second, flute; third, French horn; and fourth, French horn, flute, clarinet and oboe. Thereupon, the player, having moved the switch 58 to supply circuit 57 with current, draws out draw switches 29 and 30, and presses the first push button 54, so as to set the first jacks in such position that, when the first controller 42 is operated, said draw switches 115 will be moved automatically to active position; after which said draw switches are returned manually to inactive position. Then for the flute, draw switch 28 is drawn out, and push button No. 2 is pressed to cause 120 the second jack on said draw switch to be set in active position, after which the said draw switch is returned to inactive position. Draw switch 27 is then manually moved to active position and push button 125 No. 3 is closed to set the third jack on said switch bar, and, after the latter has been returned to inactive position, draw switches 27, 28, 29 and 30 are all drawn out and the fourth jacks thereon are all set when push 130

button No. 4 is operated. The said draw switches are then all returned to inactive position. The perforated selector or note sheet has perforations to register with the 5 duct 372 when the draw switches are to be actuated during the rendition of the composition. Hence, in the initial passage of the selector over the tracker board, a perforation registers with duct 372, and the pneumatic 10 37 moves switch bar 36 to the left into active position, and practically or almost simultaneously therewith a perforation registers with duct *c* in the tracker board, and thereupon, on the operation of the 15 first note controller 12, circuit 13, 39 is closed to cause the operation of the first controller 42, whereupon the first pair of bars 44, 45 are operated and draw switches 29 and 30 are moved to active position, so 20 that the oboe pipes F and clarinet pipes E are conditioned for operation. Then, upon the registration of a perforation in the music sheet or selector with duct A², B², or C² in the tracker board, the corresponding 25 switch bar 14, 15 or 16 is moved to active position, and switch bar 36 is released and returned to inactive position. Then, as the perforations register with the main group of note ducts in the tracker board, the several 30 individual pipes of the selected groups are caused to speak. During the time that the groups of oboe and clarinet pipes are speaking, the switch bars 14, 15 and 16 will be shifted back and forth by the controllers 35 A' B' C' as the perforations in the music sheet register with the tracker board ducts A² B² C², to select the sub-groups A, B and C for operation according to the octave of the notes to be sounded. On the completion 40 of that portion of the composition which required the No. 1 combination of clarinet and oboe, a perforation in the selector or music sheet registers with tracker-board duct 372, and a perforation registers with duct *c*#, 45 whereupon the second controller 42 will operate the second pair of draw-switch-operating fans 44, 45. (It will be understood that opening duct *c*# will not cause the corresponding pipe in any of the sub-groups 50 to speak, since the circuits 18, 20 and 22 running to said sub-groups are all opened by the switches 14, 15 and 16.) The fan 45, in moving to the right, will return the draw switches 29 and 30 to inactive position, and 55 the fan 44 will move draw switch 28 to active position to condition for operation the bank of flute pipes. Thereafter the operation of the note controllers 12 and the controllers A' B' C', as perforations in the 60 music sheet register therewith, will cause the speaking of the flute pipes in the group D. In like manner, when combination No. 3 is reached, perforations in the music sheet register with ducts 372 and *d* in the tracker board, and the operation of the third con-

troller 42 causes, through the third draw-switch operating mechanism, the return to inactive position of draw switch 28, and the movement to active position of draw switch 27, to condition the first bank or group 70 A B C of French horn pipes for operation. Finally, when combination No. 4 is reached, and perforations register with tracker board ducts 372 and *d*#, the fourth controller 42 and draw-switch actuating mechanism are 75 operated to move to active position all of the draw switches so that thereafter all of the groups of pipes will respond, upon the actuation or operation of the note controllers 12, as the particular octave, or sub-group of pipes, 80 may be selected by the controllers A' B' C'. Of course it will be understood that at any time the operator may move any one of the draw switches manually into and out of active or operative position, while the composition is being automatically rendered. 85

In Fig. 8, I have illustrated a portion of a selector or note sheet, which is indicated as a whole at 60. At the lower end, it contains the suggestions or directions as to the 90 setting of the jacks on the several draw switches for the combinations to be effected during the travel of the sheet over the tracker board, thus,—No. 1 combination—oboe and clarinet, No. 2 combination—flute, 95 No. 3 combination—French horn, and No. 4 combination—French horn, flute, oboe and clarinet. In following these directions, the operator would perform the operations which I have already described. The perforations 61 on the sheet are for registration with the tracker board duct 372, and those at 62, 63, 64 and 65, which are in practically the same lines transversely therewith, are for registration with the note ducts *c* *c*# 100 *d* *d*# in consequence of which the draw switches are operated. The perforations at 66, 67, 68 are for registration with the ducts A² B² C², as a result of which the associated controllers A' B' C' are operated to select 110 the sub-groups of pipes, and the perforations at 69 are for registration with the note ducts to cause the operation of the note controllers to cause the speaking of the individual pipes. 115

In the instrument which I have thus far described, when two or more draw switches are in active position, the corresponding pipes of the different groups will produce musical tones of the same pitch, for instance 120 as *c*, or *f*, or *a*#. I have, however, illustrated conventionally and diagrammatically in Fig. 3, an arrangement in which the independence of voices, to which I have previously referred, may be obtained. This 125 requires practically a duplication or multiplication of the mechanisms shown in Fig. 1, so far as concerns the employment of the note and octave-selecting controllers for the sounding devices, and the corresponding or 130

associated ducts in the tracker board. This is made practicable because of the small number of ducts necessary for each unit, for, as was previously stated, fifteen ducts only 5 are necessary therefor. In addition to the groups of said ducts for the several units, but one supplemental duct in the tracker board is needed for effecting the control of the stops of all the groups of sounding devices, and thus but sixty-one ducts in the 10 tracker board are needed for the complete automatic control of four complete units each having its groups of sounding devices; that is, fifteen ducts for each unit (or sixty 15 for four units) plus one duct in one of the groups of ducts for controlling all the various stops. Hence, where the tracker board is provided with the necessary ducts for say four units, since the ducts are placed in 20 practice closely together in alinement, a relatively narrow paper music sheet or selector may be utilized. While I employ a plurality of operating or controlling units, they may, if desired, all control the same 25 banks or groups of pipes or other sounding devices, so that each unit may control the operation of each group of pipes. As was understood from the previous description of the unit shown in Figs. 1 and 2, a single 30 group of twelve note ducts and twelve additional ducts (as at A², B², C², &c.) in, or forming one section of, the tracker board, may, if desired, control the operation of twelve complete groups comprising four 35 hundred and thirty-two sounding devices: but, for the sake of simplicity, I have shown in Fig. 3 only four groups of pipes and four units. In this figure, the several groups of 40 draw switches are arranged apart from each other, contrary to the actual arrangement, merely to facilitate the showing of the electric circuits. In practice all the draw stops would preferably be arranged as shown by 45 Figs. 5 and 6, in order to have all the draw switches and their jacks 43 within the range of action of a single pair of fans 44, 45, and within the range of a single pneumatic 52. The branch circuits for controlling the 50 operation of these groups of pipes are connected with the respective contacts on the draw switches of the different units.

The groups A³ D E F of sounding devices, for the sake of explanation, may be considered as pipes for producing the tones of the 55 French horn, the flute, the clarinet, and the oboe, respectively, as previously described. Each group consists of three sub-groups tuned in sequence, each sub-group comprising pipes for producing the twelve tones of 60 a chromatic scale, as explained in connection with Fig. 1. The tracker board 70 is shown as having four sections, or four groups 71, 72; 73, 74; 75, 76; and 77, 78 of ducts for controlling the note controllers and the additional controllers A', B', C', as already 65

described, by which the sub-groups of each group of pipes may be sounded in sequence. I provide connections by which each group of said controllers in one unit will control each of the groups of sounding devices. 70 For each unit, I have shown conventionally four groups of four draw switches, each group being associated with one group of ducts in, or forming one section of, the tracker board, and being so arranged and 75 connected in multiple with the groups of pipes that each group of draw switches may control the pipes of each of the four groups A³ D E and F, though in practice these groups of draw switches may be arranged 80 as shown in Figs. 6 and 7 as hereinafter explained. I have not attempted on the drawings to illustrate all of the complete circuits and the electrical connections, as it would be confusing and complicated 85 and would serve no useful purpose. I have, however, illustrated these connections sufficiently for any organ builder or manufacturer of musical instruments familiar with the art, to reproduce the invention, and I 90 have used as far as possible the same reference characters for the same parts which were previously explained. I will explain one group of devices controlled from one section of the tracker board, the others being identical therewith. On the admission 95 of air to the ducts 71, by reason of the registration therewith of perforations in the note sheet or selector, the note controllers are actuated. The controllers A' B' C' are 100 operated by the admission of air to ducts 72. These controllers correspond to those at 12 and A' B' C' in Fig. 1. The circuits 13, 18, 20 and 22 in Fig. 3 also correspond with those similarly numbered in Fig. 1. 105

The four draw switches of each unit are provided with jacks which may be set, as previously explained, and they are automatically moved into and out of operation. The corresponding contacts of draw switch 110 30 of each unit are all electrically connected in multiple by conductors inclosed in a cable 80 with the electromagnetic valve controllers of group F of oboe pipes; and likewise the contacts of draw switches 29, 115 28 and 27 are connected by conductors in cables 81, 82 and 83 with the groups of pipes E, D and A³. By this arrangement, on operating one of the four draw switches in any unit, any corresponding group of pipes 120 may be caused to speak on the operation of the controllers of that particular unit. Thus, by moving to active position a different draw switch in each of the units, the four groups of pipes may be caused to 125 speak independently of each other, under control of the different sections of the tracker board. Of course the selector or note sheet will be divided transversely into as many sections as there are units or sec- 130

tions of the tracker board, and each section will be properly perforated for the control of the various instrumentalities constituting each unit.

For controlling the operation of all of the draw switches, I have shown the last section of the tracker board as being provided with a supplemental duct 372 connected with the pneumatic controller 37 for operating the switch bar 36 (these parts corresponding to those similarly numbered in Fig. 3) in consequence of which the pneumatic note controllers of the fourth unit (counting from the right to left) may control the controllers 42 for operating the draw switches. To show how this may be accomplished, reference may be had again to Figs. 6 and 7, which show the group of note controllers 12 of the last or fourth unit. The sixteen draw switches arranged in four groups, each having those indicated at 27, 28, 29 and 30, are all shown as arranged in a horizontal plane as in Fig. 5, and each has the twelve jacks which I previously described. These jacks are arranged in rows transversely of the draw switches as previously explained. Hence, when the switch bar 36 is moved to the left to partially close circuits 13, 39, the operation of the several note pneumatics will cause the operation of the corresponding controlling pneumatics 42, and the associated draw-switch-operating bars 44, 45, all in the manner previously explained. Thus, from the single section of the tracker board, containing the single supplemental duct 372, the draw switches of all four units are automatically controlled. Any suitable number of groups of sounding devices may be employed in each unit; and the number of units which may be controlled from a single tracker board is limited only by the practicable width of the note sheet or selector.

In Fig. 8, to which I have already referred, I have shown the selector or note sheet as provided with longitudinal lines 90, to divide it into four sections or strips corresponding to the sections of the tracker board. In each section of the sheet are located the various perforations which I previously described for registration with the ducts in the corresponding sections of the tracker board. When the draw stops are to be operated manually by the operator or player, symbols may be located in the several sections of the note sheet for indicating to the operator which draw switches are to be operated, and when, so as to produce predetermined effects. Even where the draw switches are controlled by the note sheet and the described controllers, the note sheet may be provided with the symbols as shown, so that, if the player wishes to add different voices, he can determine which of the other draw switches he can operate.

Of course it will be understood that any ordinary mechanism may be used for feeding the note sheet or selector over the tracker board to cause the various perforations therein to register with the proper ducts in the tracker board.

I have, for convenience in describing my invention, explained its use in connection with an electro-pneumatic pipe organ, but of course it could be employed in connection with instruments in which the sounds are produced either by the use of hammers or by electro-magnetically vibrated strings or bodies. For instance, I may with facility embody the invention in an instrument comprising a group of strings and hammers, groups of pipes to produce the effect of wind instruments, and groups of instruments to produce the effects of the violin and cello. The various mechanisms for operating these several groups are well known, and it would be superfluous to show them, since such mechanisms do not *per se* constitute any part of the present invention; and, while, as I have stated, the particular embodiment of invention shown includes controllers which are pneumatically operated, I should regard the controllers for the same purpose which were actuated or operated either mechanically or electrically as within the scope of my invention as hereinafter claimed.

So far as I am aware, I am the first to control a group of sounding devices, tuned to furnish the notes of a scale and divided into sub-groups of consecutive devices, by a single group of selector-controlled note controllers equal in number to one sub-group, and additional controllers for determining and controlling which sub-group is to respond to the action of the primary controllers.

The group of sounding devices I have referred to as consisting of sub-groups which are in sequence or consecutively tuned, and it will be understood that each sub-group may consist of one or more octaves. As shown, each sub-group of sounding devices consists of twelve which are tuned chromatically, but I should not consider it a departure from my invention if each sub-group of the entire group comprised more or less than twelve sounding devices. In stating that the sub-groups are tuned in sequence, I mean that they are preferably all of the same voice, and, when taken as an entire group, comprise a chromatic scale of as many octaves as may be desired.

Having thus explained the nature of my said invention and described a way of making and using the same, although without attempting to set forth all of the forms in which it may be made or all of the modes of its use, what I claim is:

1. An automatic musical instrument, com-

- prising a plurality of sounding devices tuned to furnish the notes of a scale and divided into sub-groups consisting of consecutive devices, a group of selector-controlled note controllers equal in number to the sounding devices of one sub-group, and selector-controlled mechanism for selecting said sub-groups for operation. 65
2. An automatic musical instrument, comprising a plurality of sounding devices tuned to furnish the notes of a scale and divided into sub-groups consisting of consecutive devices, a group of selector-controlled note controllers equal in number to the sounding devices of each sub-group, and selector-controlled controllers, one for each said sub-group of sounding devices, for selecting or conditioning said sub-groups for operation in any predetermined order. 70
- 10 3. An automatic musical instrument, comprising a plurality of sounding devices tuned to furnish the notes of a scale and divided into sub-groups consisting of consecutive devices, a group of note-controllers equal in number to the sounding devices of one sub-group, controllers equal in number to said sub-groups for selecting said sub-groups for operation, and a tracker board having selector-controlled means for energizing all of 75
- 15 said controllers. 80
4. An automatic musical instrument, comprising a plurality of sounding devices having a compass of several octaves and divided into sub-groups each having a compass of one octave, a tracker board having connected therewith note controllers equal in number to the sounding devices of a single octave, and selector-controlled mechanism for causing said controllers to control the operation of all of said sounding devices. 85
- 20 5. An automatic musical instrument, comprising a tracker board, and note controllers equal in number to the notes of an octave, in combination with a plurality of sounding devices tuned to furnish the notes of a scale comprising a plurality of octaves, and selector-controlled mechanism by which each note controller may cause the operation of the corresponding sounding device of 90
- 25 each octave independently of the like sounding devices of the other octaves. 95
6. An automatic musical instrument, comprising a tracker board having twelve ducts and twelve associated pneumatic controllers, 100
- 30 a plurality of sounding devices tuned to furnish the notes of a scale and divided into a plurality of sub-groups, each consisting of consecutive devices for one octave, and selector-controlled mechanism comprising additional ducts in the tracker board and associated pneumatic controllers,—one duct and its associated controller for each sub-group of sounding devices,—for selecting for operation by said first-mentioned controllers 105
- 35 the sub-groups of sounding devices in any predetermined order. 110
7. An automatic musical instrument, comprising a plurality of sounding devices tuned to furnish the notes of a scale and divided into sub-groups consisting of consecutive devices, a set of note controllers equal in number to the sounding devices of a sub-group, a group of controllers equal in number to said sub-groups, means operated by said last-mentioned controllers for conditioning said sub-groups of sounding devices for operation by said note controllers, and a tracker board having operative connections to said note controllers and said second-mentioned controllers. 115
- 40 8. An automatic musical instrument, comprising a tracker board and a set of twelve note controllers, a series of sounding devices tuned to furnish the notes of a scale and divided into sub-groups each consisting of twelve sounding devices, and selector-controlled mechanism for operatively and selectively connecting the note controllers with each of the sub-groups of sounding devices, in consequence of which the entire number of 120
- 45 sub-groups of sounding devices may be controlled in operation by the single set of note controllers. 125
9. An automatic musical instrument, comprising a plurality of sounding devices tuned to furnish the notes of a scale and divided into sub-groups each having the compass of one octave, a tracker board having twelve ducts, one for each tone of the octave, and selector-controlled mechanism for conditioning for operation the sounding devices of each sub-group independently of the corresponding sounding devices of the other groups, on registration with said ducts in said tracker board of perforations in the 130
- 50 selector or note sheet passing said board. 135
10. An automatic musical instrument, comprising a plurality of sounding devices having a compass of several octaves and divided into sub-groups each having a compass of one octave, a tracker board having ducts equal in number to the tones of an octave, and selector-controlled means by which the opening of any one of said ducts will cause the speaking of a corresponding 140
- 55 sounding device in any one of said octaves without causing the speaking of the sounding devices of the other octaves. 145
11. An automatic musical instrument, comprising a plurality of differently voiced main groups of sounding devices, each main group comprising a plurality of sounding devices tuned to furnish the notes of a scale and divided into sub-groups consisting of consecutive devices, and selector-controlled mechanism for causing said groups and sub-groups to speak independently of each other, said mechanism comprising a plurality of 150
- 60

- groups of note controllers each group thereof being equal in number to the sounding devices of a single sub-group, and a plurality of additional controllers with each group 5 of note controllers and equal in number to the sub-groups of a main group of sounding devices for selecting for operation the sub-groups of the corresponding main groups of sounding devices.
- 10 12. An automatic musical instrument, comprising a plurality of main groups of sounding devices, each main group being tuned to furnish the notes of a scale and being divided into sub-groups consisting of 15 consecutive devices, selector-controlled mechanism for selecting any one of the main groups for operation, selector-controlled mechanism for selecting for operation any sub-group of the main group thus selected, 20 and note controllers equal in number to the sounding devices of a sub-group for selecting for speaking the individual sounding devices of the sub-groups thus selected.
13. An automatic musical instrument, 25 comprising a plurality of groups of sounding devices each having a compass of several octaves and divided into sub-groups each having a compass of one octave, a tracker board having a plurality of groups 30 of selector-controlled note controllers, each group of note controllers being equal in number to the sounding devices of one octave, and selector-controlled controllers associated with each group of note controllers 35 and equal in number of the sub-groups of a group of sounding devices for selecting the sub-groups of sounding devices for operation.
14. An automatic musical instrument, 40 comprising a plurality of groups of sounding devices, a draw switch for each group, a single series of note controllers for the sounding devices of the several groups, and selector-controlled mechanism by which said 45 note controllers may automatically control the operation of said draw switches.
15. An automatic musical instrument, 50 comprising a group of sounding devices, a group of selector-controlled note controllers, a draw switch for said group of sounding devices, and selector-controlled mechanism by which one of said note controllers causes 55 the operation of said draw switch.
16. An automatic musical instrument, 60 comprising a group of sounding devices, a group of selector-controlled note controllers, a draw switch for said group of sounding devices, and selector-controlled controllers for conditioning for operation by said first-mentioned note controllers the draw switch and the sounding devices in alternation.
17. An automatic musical instrument, 65 comprising a plurality of sounding devices, a draw switch therefor, a tracker board hav-
- ing connected therewith a series of note controllers, and selector-controlled mechanism for selecting the draw switch and the sounding devices for operation by said note controllers. 65
18. An automatic musical instrument, 70 comprising a plurality of groups of sounding devices, a draw switch for each group, a group of selector-controlled note controllers, an additional selector-controlled controller, and mechanism controlled by said last-mentioned controller in consequence of which 75 said note controllers may cause the selective automatic operation of said draw switches.
19. An automatic musical instrument, 80 comprising a plurality of differently voiced groups of sounding devices, draw switches therefor, a tracker board having a plurality of groups of ducts and associated note controllers for causing the speaking of the sounding devices, said tracker board having 85 an additional duct and associated mechanism whereby said draw switches may be selectively operated by the ducts and associated note controllers of one of the first-mentioned groups of ducts. 90
20. An automatic musical instrument, 95 comprising a plurality of differently voiced groups of sounding devices each having a compass of several octaves and each divided into sub-groups having a compass of one octavo, draw switches for said groups, and a tracker board having a plurality of groups of ducts,—each group having twelve ducts plus a number of ducts equal to the number 100 of octaves in one of said groups of sounding devices,—and mechanism associated therewith for selecting and conditioning said sub-groups of sounding devices for operation, said tracker board also having a supplemental duct and mechanism associated 105 therewith by which one of said groups of twelve ducts and associated mechanism may cause the automatic selective operation of said draw switches.
21. An automatic musical instrument, 110 comprising a group of sounding devices having a compass of several octaves and divided into sub-groups each having a compass of one octave, a draw switch for said group, and a tracker board having twelve 115 ducts and note controllers, and additional ducts and controllers equal in number to said sub-group of sounding devices for causing the selective operation of said sounding devices independently of each other, said 120 tracker board having a supplemental duct and controller for causing the operation of said draw switch by one of said note controllers. 125
22. An automatic musical instrument, comprising a tracker board and note controllers for controlling the operation of a group of sounding devices, a draw switch

for the sounding devices, mechanism by which said stop may be operatively controlled by one of the note controllers, and additional controlling mechanism, including 5 a duct in the tracker board, for controlling the operation of said draw switch by said note controller.

23. An automatic musical instrument, comprising a group of sounding devices 10 tuned to furnish the notes of a scale and divided into sub-groups of consecutive devices, a set of note-controllers equal in number to the sounding devices of one sub-group for controlling the individual sounding devices of any sub-group, controllers equal in 15 number to the total number of sub-groups for selecting for operation any one of the sub-groups, a tracker board connected with all said controllers, and a selector or note 20 sheet having a series of perforations for controlling the first-mentioned controllers and a second series of perforations for controlling said second-mentioned controllers.

24. An automatic musical instrument, 25 comprising a plurality of groups of sounding devices, each tuned to furnish the notes of a scale and divided into sub-groups of consecutive devices, a set of note controllers equal in number to the sounding devices of 30 one sub-group for controlling the individual sounding devices of any group, addi-

tional controllers equal in number to the total number of sub-groups for selecting for operation any one of the sub-groups, a supplemental controller for controlling the selection of the said groups of sounding devices for operation, and a selector having a series of perforations for controlling the note controllers, a series of perforations for controlling the additional or second-mentioned controllers, and a series of perforations for controlling the supplemental or third-mentioned controller. 35 40 45

25. An automatic musical instrument, comprising a group of sounding devices, tuned 45 to furnish the notes of a scale and divided into sub-groups of consecutive devices, a selector or note sheet having a series of perforations for selecting for operation any sub-group and having a series of perforations 50 for selecting for operation individual sounding devices of the sub-group thus selected, a tracker board, controllers connected therewith equal in number to said sub-groups and controlled by said selector for selectively 55 conditioning for operation any one of said sub-groups and note-controllers equal in number to the sounding devices of a sub-group also connected to said tracker board.

In testimony whereof I have affixed my 60 signature.

ERNEST M. SKINNER.
